ALEXANDER G. SIMKINS, OF GRIMES, CALIFORNIA.

AUTOMATIC RAILROAD-CROSSING-GATE-OPERATING MECHANISM.

1,282,005.

Specification of Letters Patent. Patented Oct. 15, 1918.

Application filed February 26, 1917. Serial No. 151,017.

To all whom it may concern:

Be it known that I, ALEXANDER G. SIMKINS, citizen of the United States, residing at Grimes, in the county of Colusa and State 5 of California, have invented certain new and useful Improvements in Automatic Railroad-Crossing - Gate - Operating Mechanism, of which the following is a specification.

This invention is an automatic gate operating mechanism for gates at railroad crossings, adapted to be actuated by a train to 10 close the gate before the train reaches the crossing and to open the gate after the train has passed the crossing.

Referring to the drawings:

Figure 1 is a side elevation of the right half of the invention, with the mechanism set to be actuated to close the gate by a train approaching from the right.

Fig. 2 is a side elevation of the left half of the invention as illustrated in Fig. 1.

Fig. 3 is a side elevation of the right half of the invention with the mechanism set to be actuated to close the gate by a train approaching from the left.

Fig. 4 is a side elevation of the left half of the invention as illustrated in Fig. 2.

Figs. 5, 6 and 7 are views of one of the sliding bars of the mechanism in its successive operating positions.

Fig. 8 is a view of an element of the mechanism adapted to be actuated to cause the mechanism to close the gate after the train has passed the gate to the left thereof.

Figs. 9 to 15 inclusive are diagrammatic views illustrating the operation of certain parts of the invention.

Fig. 16 is a cross sectional view of the track taken on line 16 of Fig. 1 showing the 40 tripping element.

Fig. 17 is a view of certain parts of the resetting elements showing how the two elements are connected.

Figs. 18 to 20 inclusive are views of the 45 other sliding bar in its successive operating positions.

The invention includes a gate 1 comprising a pair of weighted gate members 2 and 3, pivoted respectively at 4 and 5 on standards 6 and 7, and provided with weights 8 and 9 adapted to swing said gate members into open position.

An arm 10 is fixed to the gate member 2 at the side of the pivot 4 opposite the weight 55 8, to the lower end of which arm is connect-

ed a cable 11. Said cable extends over a pulley 12 mounted on standard 6, pulley 13 mounted on a standard 14, and pulley 15 mounted on a frame 16, and it is connected to a weight 17 which is adapted when released to overbalance the weight 8 and pull the gate member 2 down by means of the cable. From the weight 17 said cable extends over pulleys 18 and 19 on the frame 16 and is connected to the upper end of a lever 60 20 pivoted at 21 to a standard 22. To the lower end of said lever is connected one end of a rod 23, the other end of which is connected to the lower end of a lever 24, pivoted at 25 to a standard 26.

On the upper end of lever 24 is a segmental element 27 having two shoulders 28 and 29 adapted to be engaged by a dog 30 pivoted to the track rail 31 at 32. The dog 30 has an upstanding arm 33 which projects 70 through a slot 34 in a bar 35 slidably mounted on rollers 36 journaled on the rail 31. In Fig. 2 the dog 30 is in engagement with shoulder 29 whereby the gate member 2 is held in open position through the medium 75 of lever 24, rod 23, lever 20 and cable 11 as shown in Fig. 1.

A tripping arm 40 is connected to the lever 24 and extends upwardly between and above the rails of the track when the dog 30 80 is out of engagement with the shoulders 28 and 29, and is adapted to be engaged by the cowcatcher of the engine to swing the lever 24, and, through its connections swing the gate member 2 into open position, and bring 85 the shoulder 28 or 29 into engagement with the dog 30, according to the direction of travel of the engine, to lock the gate member 2 in open position. A tripping element 45 is provided to be operated by the cow- 90 catcher of the engine for moving the bar 35 to the left to cause the end of the slot 34 to engage the dog arm 33 to disengage the dog from the shoulders 28 and 29, so that the weight 17 may drop and swing 95 down the gate member 2 into closed position. Said tripping element comprises a shaft 46 journaled in bearings 47 secured to the under side of the track rails, an upstanding arm 48 projecting upwardly between 100 and above the track rails, in the path of the cowcatcher of the engine, and an upstanding arm 49 which projects through a slot 50 at the right end of the bar 35.

A bar resetting element is provided for 110

returning the bar to its initial position so that the dog 30 may drop into engagement with the shoulder 28 when the train has passed and actuated the tripping element 45 and the gate members have been swung down into closed position. Said resetting element comprises a weighted shaft 51 journaled in bearings 52 secured to the under side of the track rails, an arm 53 projecting upwardly between and above the track rails in the path of the cowcatcher, an engaging arm 54, and an angle lever 55 pivoted at 56 to the track rail 31, the arm 57 of which extends through a slot 58 in bar 35 and the arm 59 thereof being adapted to be engaged by the arm 54 when the arm 53 and shaft 51 are moved to the left by the engagement of the cowcatcher with the arm 53.

The structure of the gate member 3 and its operating mechanism are similar to the structure of the gate member 2 and its operating mechanism. The operating mechanism for the gate member 3 will now be described.

A cable 60 is connected to the arm 61 of the gate member 3, (which arm corresponds to arm 10 of gate 2), and passes over pulleys 62 on standard 7, pulley 63 on standard 64, pulley 65 on frame 66 and is connected to a weight 67 adapted when released to overcome the weight 9 and swing the gate member 2 down into closed position. Said cable extends from the weight 67 over pulleys 68 and 69 on the frame 66, and is connected to the upper end of lever 70 pivoted at 70' to a standard 72. The rod 23 while connected to levers 20 and 24 is also connected to the lower end of lever 70 and to the lower end of a lever 71 which is pivoted at 72 to standard 73. A segmental element 74 is secured to the upper end of lever 71 and has two shoulders 75 and 76 adapted to be engaged by a dog 77 pivoted at 78 to the track rail 79 to lock the gate member 3 in open position. The dog 77 has an arm 80 which projects through a slot 81 in a bar 82 slidably mounted at the side of rail 79. A tripping arm 83 is connected to the lever 71 and extends upwardly between and above the track rails when the dog 77 is out of engagement with the shoulders 75 and 76, and is adapted to be engaged by the cowcatcher of the engine to swing the lever 71 and through its connections swing the gate member 3 into open position and bring the shoulder 75, or 76, into engagement with the dog 77, according to the direction of travel of the engine, to lock the gate member 3 in open position.

A tripping element 85, similar to tripping element 45, is provided for moving the bar 82 to the right to cause the end of slot 81 to engage the dog arm 80 to disengage the dog from the shoulders 75 and 76, so that the weight 67 may drop and swing down the gate member 2 into closed position. Said

tripping element comprises a shaft 86 journaled in bearing 87 secured to the under side of the track rails, an arm 88 extending upwardly from said shaft between and above the track rails in the path of the cowcatcher 70 of the engine and an arm extending upwardly from said shaft through a slot 89 at the left end of the bar 82. A bar resetting element 90 is provided for returning the bar 82 to its initial position so that the dog 77 75 may drop into engagement with the shoulder 76 when the train has passed and actuated the tripping element 85 and the gate members have swung down into closed position. Said resetting element comprises a weighted shaft 91 journaled in bearings 92 secured to the under side of the track rails, an arm 93 projecting upwardly between and above the track rails in the path of the cowcatcher, an engaging arm 94, and an angle lever 95 pivoted at 96 to the track rail 79, the arm 97 of which extends through a slot 98 in the bar 82, and the arm 99 thereof being adapted to be engaged by the arm 94 when the arm 93 and shaft 91 are moved to the right by the engagement of the cowcatcher with arm 93. A rod 100 is connected at its respective ends to an arm 101 depending from the shaft 86 of tripping element 85 and to arm 48 of tripping element 45, whereby said tripping elements are operated synchronously when either is operated by the cowcatcher of the engine, and the bars 35 and 82 are moved to disengage both dogs 30 and 77 synchronously from the shoulders of 100 segmental members 27 and 74, so that both gate members may swing down together under the influence of their weights. Arms 105 and 106 are respectively provided on the angle levers 55 and 95, which arms are 105 connected by a rod 107, whereby the angle levers are caused to operate synchronously. The operation of the invention is as follows:

Assuming the parts to be in the position shown in Figs. 1, 2 and 9, and a train is approaching the crossings from the right side, the cow-catcher of the engine first engages the arm 48 of the tripping element 45 and by the engagement of the arm 49 with the end of slot 50 moves the bar 35 to the left; during which movement of the bar the end of the slot 34 engages the arm 33 and lifts the dog 30 out of engagement with the shoulder 29, whereupon the weight 17 drops and swings the gate member 2 down into closed position and swings the lever 20 and lever 24 and arm 40 through rod 23 into vertical position, as shown in dotted lines in Figs. 1 and 2.

During said operations the rod 100 is 125 moved to the left by arm 48 and by means of arm 101 the tripping element 85 is actuated and the arm 88 thereof engages the end of slot 89 and moves the bar 82 to the right; which movement of the bar 82 causes the end 130

of the slot 81 to engage the arm 80 and disengage the dog 77 from the shoulder 75, whereupon the weight 67 drops and swings the gate member 3 down into closed position, and also swings the lever 71 and arm 83 through rod 23 into vertical position, as shown in dotted lines in Figs. 1 and 2. The connection of the levers 20 and 70 by rod 23 insures synchronous operation of the gate members 2 and 3. As the bars 35 and 82 are respectively shifted to the left and right during said operations, the arms 57 and 97 of angle levers 55 and 95 respectively, of the resetting elements are engaged by the ends of the slots 58 and 98 respectively in said bars and swing to the left and right respectively, and the arms 59 and 99 are swung up adjacent the arms 54 and 94 of the resetting elements. As the train travels farther to the left of the tripping element 45, the cowcatcher engages the arm 53 of the resetting element and swings said arm to the left, which causes the arm 54 to engage the arm 59 of the angle lever 55, and swing the arm 57 thereof to the right, whereupon the arm 57 engages the right end of slot 58 and shifts the bar 35 to the right back to its initial position, during which movement the end of the slot 50 engages arm 49 and resets the tripping element 45, and the end of the slot 34 shifts to the right and permits the end of the dog 30 to drop upon the curved surface of the segmental element 27, as shown in Fig. 8. As the angle lever 55 is operated by the arm 54, the angle lever 95, through arms 105 and 106 and rod 107, are swung to the left, whereupon the arm 97 engages the end of the slot 98 and shifts the bar 82 back to its initial position, during which movement of the bar the end of the slot 89 engages arm 88' and resets the tripping element 85 and the end of the slot 80 shifts to the left and permits the end of the dog 77 to drop upon the curved surface of the segmental member 74. When the train has traveled past the gate, the cowcatcher engages the arm 40, which is then in its vertical position, as shown in dotted lines in Fig. 2, and swings said arm to the left, whereupon the lower end of the lever 24 is swung to the right and the levers 70, 20 and 71, through rod 23 are swung into the positions shown in Figs. 3 and 4, during which movement the levers 20 and 70 through cables 11 and 60, lift the weights 17 and 67, and the weights 8 and 9 in turn swing the gate members 2 and 3 into open position and open the crossing.

When said parts have been swung into the position shown in Figs. 3 and 4, the dogs 30 and 77 drop into engagement with the shoulders 28 and 76 of the segmental members 27 and 74 and lock the parts in said position and allow the gate to remain open under the influence of weights 8 and 9. The mecha-

nism is now again set to be actuated to close the gate by a train traveling in either direction.

Assuming the parts to be in the position shown in Figs. 3 and 4 and a train is approaching the crossing from the left side, the cowcatcher of the engine first engages the arm 88 of tripping element 85 and by the engagement of the arm 88' with the end of slot 89 moves the bar 82 to the right, during which movement of the bar the end of the slot 81 engages the arm 80 and lifts the dog 77 out of engagement with shoulder 76, whereupon the weight 67 drops and swings the gate member 3 down into closed position, and swings the arm 70 and lever 71 and arm 83 through rod 23 into vertical position as shown in dotted lines in Figs. 1 and 2. During said operations the rod 100 is moved to the left by arm 101 and the tripping element 45 is actuated and the arm 49 engages the end of slot 50 and moves the bar 35 to the left, which movement of the bar causes the end of the slot 34 to engage the arm 33 and disengage the dog 30 from the shoulder 28, whereupon the weight 17 drops and swings the gate member 2 down into closed position and also swings the lever 24 and arm 40, through rod 23, into vertical position as shown in dotted lines in Figs. 1 and 2.

As the bars 82 and 35 are respectively shifted to the right and left during said operations, the arms 97 and 57 of angle levers 95 and 55 respectively of the resetting elements are engaged by the ends of the slots 98 and 58 respectively in said bars and swung to the right and left respectively, and the arms 99 and 59 are swung up adjacent the arms 94 and 54 of the resetting elements. As the train travels farther to the right of the tripping element 85, the cowcatcher engages the arm 93 of the resetting element and swings said arm to the right which causes the arm 94 to engage the arm 99 of angle lever 95 and swing the arm 97 to the left, whereupon the arm 97 engages the left end of the slot 98 and shifts the bar 82 to the left back to its initial position, during which movement the end of the slot 89 engages the arm 88' and resets the tripping element 85 and the end of the slot 81 shifts to the left and permits the end of the dog 77 to drop upon the curved surface of the segmental element 74.

As the angle lever 95 is operated by the arm 94, the angle lever 55, through arms 106 and 105 and rod 107, are swung to the left, whereupon the arm 57 engages the end of the slot 58 and shifts the bar 35 back to its initial position, during which movement of the bar the end of the slot 50 engages the arm 49 and resets the tripping element 45, and the end of the slot 34 shifts to the right and permits the end of the dog 30 to drop upon the curved surface of the segmental

member 27. When the train has traveled past the gate, the cowcatcher engages the arm 83, which is then in its vertical position, as shown in dotted lines in Fig. 1, and 5 swings said arm to the right, whereupon the lower end of the lever 71 is swung to the left and the levers 20, 70 and 24, through rod 23, are swung to the left into the position shown in Figs. 1 and 2, during which 10 movement the levers 70 and 20, through cables 60 and 11, lift the weights 67 and 17, and the weights 9 and 8 in turn swing down the gate members 3 and 2 into open position and open the gate. When said parts have 15 been swung into the position shown in Figs. 1 and 2, the dogs 77 and 30 drop into engagement with the shoulders 75 and 29 of the segmental members 74 and 27 and lock the parts in said position and allow the gate 20 to remain open. The mechanism is now again set to be actuated to close the gate by a train traveling in either direction.

Having described my invention what I claim as new and desire to secure by Letters Patent is:

1 A 12

1. A railroad crossing gate mechanism comprising a gate for the crossing, means actuated by the approaching train to close said gate before the train reaches the crossing, means actuated by the train for opening said gate after the train has passed the crossing, and means actuated by the train for resetting said gate closing means after the gate has been opened.

35 2. A railroad crossing gate mechanism comprising a gate for the crossing, a lever, a dog-coacting part on said lever, a weight connected to said gate, a lever connected to said weight, a rod connecting said levers, a
40 dog for engaging said dog-coacting part and holding said weight connected lever in such position that said lever holds said weight up, so that said gate may remain in open position, a reciprocative bar for en-
45 gaging said dog and a tripping element engaging said bar and adapted to be engaged by the approaching train to shift said bar to disengage said dog from said dog-coacting part and allow said weight to drop and
50 close said gate.

3. A railroad crossing gate mechanism comprising a gate for the crossing, a lever, a dog-coacting part on said lever, a weight connected to said gate, a lever connected to said weight, a rod connecting said levers, a dog for engaging said dog-coacting part and holding said weight connected lever in such position that said lever holds said weight up, so that said gate may remain in open position, a reciprocative bar for engaging said dog and a tripping element engaging said bar and adapted to be engaged by the approaching train to shift said bar to disengage said dog from said dog-coacting part and allow said weight to drop.

and close said gate, and means for resetting said parts after the train has passed the crossing, whereby said weight is raised and the gate is opened.

4. A railroad crossing gate mechanism 70 comprising a gate for the crossing, a lever, a dog-coacting part on said lever, a weight connected to said gate, a lever connected to said weight, a rod connecting said levers, a dog for engaging said dog-coacting part 75 and holding said weight connected lever in such position that said lever holds said weight up, so that said gate may remain in open position, a reciprocative bar for engaging said dog and a tripping element 80 engaging said bar and adapted to be engaged by the approaching train to shift said bar to disengage said dog from said dog-coacting part and allow said weight to drop and close said gate, a resetting element adapted 85 to be actuated by the train after passing said tripping element to return said bar and said tripping element to their initial position, and an arm on said first lever to be engaged by the train after the train has 90 passed the crossing, to swing said lever and the weight connected lever to raise said weight to open the gate.

5. A railroad crossing gate mechanism comprising a gate for the crossing, said gate comprising two gate members, a locking lever for each gate, a dog-coacting part on each lever, a weight connected to each gate, a lever connected to each weight, a rod connecting each locking lever to one of said weight connected levers, a dog for engaging the dog-coacting part on each locking lever, and respectively holding said weights up so that said gate members may remain in open position, a reciprocal bar for engaging each dog and a tripping element engaging each bar, one of said tripping elements being adapted to be engaged by a train approaching in one direction and the other tripping element being adapted to be engaged by a train approaching in the other direction to shift either bar to disengage the dog from the dog-coacting part of either locking lever and allow either weight to drop and close either gate member. 115

6. A railroad crossing gate mechanism comprising a gate for the crossing, said gate comprising two gate members, a locking lever for each gate, a dog-coacting part on each lever, a weight connected to each gate, a lever connected to each weight, a rod connecting each locking lever to one of said weight connected levers, a dog for engaging the dog-coacting part on each locking lever, and respectively holding said weights up so that said gate members may remain in open position, a reciprocative bar for engaging each dog and a tripping element engaging each bar, one of said tripping elements being adapted to be engaged by a train ap- 125 130

proaching in one direction and the other tripping element being adapted to be engaged by a train approaching in the other direction to shift either bar to disengage

- 5 the dog from the dog-coacting part of either locking lever and allow either weight to drop and close either gate member, and means for resetting the operated parts for each gate member after the train has passed 70
- 10 the crossing, whereby the weight connected to the operated gate is raised to open the gate.

7. A railroad crossing gate mechanism comprising a gate for the crossing, said gate

- 15 comprising two gate members, a locking lever for each gate, a dog-coacting part on each lever, a weight connected to each gate, a lever connected to each weight, a rod connecting each locking lever to one of said 75
- 20 weight connected levers, a dog for engaging the dog-coacting part on each locking lever, and respectively holding said weights up so that said gate members may remain in open position, a reciprocative bar for 80
- 25 engaging each dog and a tripping element engaging each bar, one of said tripping elements being adapted to be engaged by a train approaching in one direction and the other tripping element being adapted to be 85
- 30 engaged by a train approaching in the other direction to shift either bar to disengage the dog from the dog-coacting part of either locking lever and allow either weight to drop and close either gate member, and a 90
- 35 resetting element for each bar adapted to be actuated by the train after passing the tripping element to return the operated bar and tripping element to their initial position, and an arm on each locking lever to be 95
- 40 engaged by the train after the train has passed the crossing to swing said lever and its associate weight connected lever to raise the lowered weight to open the closed gate. 100

8. A railroad crossing gate mechanism

- 45 comprising a gate for the crossing, said gate comprising two gate members, a locking lever for each gate, a dog-coacting part on each lever, a weight connected to each gate, a lever connected to each weight, a rod connecting each locking lever to one of said 105
- 50 weight connected levers, a dog for engaging the dog-coacting part on each locking lever, and respectively holding said weights up so that said gate members may remain in 110
- 55 open position, a reciprocative bar for engaging each dog and a tripping element engaging each bar, one of said tripping elements being adapted to be engaged by a train approaching in one direction and the 115
- 60 other tripping element being adapted to be engaged by a train approaching in the other direction to shift either bar to disengage the dog from the dog-coacting part of either locking lever and allow either weight to drop and close either gate member, a re- 120
- 65

setting element for each bar adapted to be actuated by the train after passing the tripping element to return the operated bar and tripping element to their initial position, and an arm on each locking lever to be 70

engaged by the train after the train has passed the crossing to swing said lever and its associate weight connected lever to raise the lowered weight to open the closed gate, means connecting both tripping elements so 75

that both elements will be actuated to shift both bars and disengage both dogs from the dog-engaging parts of both locking levers synchronously.

9. A railroad crossing gate mechanism 80

- comprising a gate for the crossing, said gate comprising two gate members, a locking lever for each gate, a dog-coacting part on each lever, a weight connected to each gate, a lever connected to each weight, a rod connecting each locking lever to one of said 85
- weight connected levers, a dog for engaging the dog-coacting part on each locking lever, and respectively holding said weights up so that said gate members may remain in open 90
- position, a reciprocative bar for engaging each dog and a tripping element engaging each bar, one of said tripping elements being adapted to be engaged by a train approaching in one direction and the other 95
- tripping element being adapted to be engaged by a train approaching in the other direction to shift either bar to disengage the dog from the dog-coacting part of either locking lever and allow either weight to 100
- drop and close either gate member, a resetting element for each bar adapted to be actuated by the train after passing the tripping element to return the operated bar and tripping element to their initial position, 105
- and an arm on each locking lever to be engaged by the train after the train has passed the crossing to swing said lever and its associate weight connected lever to raise the lowered weight to open the closed gate 110
- means connecting both tripping elements so that both elements will be actuated to shift both bars and disengage both dogs from the dog-engaging parts of both locking levers synchronously, and means connecting both 115
- of said weight connected levers so that both levers may be swung to enable both weights to drop and close both gate members synchronously or to raise both weights to enable both gate members to swing open synchronously. 120

10. A railroad crossing gate mechanism 125
- comprising a gate for the crossing, said gate comprising two gate members, a locking lever for each gate, a dog-coacting part on each lever, a weight connected to each gate, a lever connected to each weight, a rod connecting each locking lever to one of said 130
- weight connected levers, a dog for engaging the dog-coacting part on each locking lever. 130

and respectively holding said weights up so that said gate members may remain in open position, a reciprocative bar for engaging each dog and a tripping element engaging each bar, one of said tripping elements being adapted to be engaged by a train approaching in one direction and the other tripping element being adapted to be engaged by a train approaching in the other direction to shift either bar to disengage the dog from the dog-coacting part of either locking lever and allow either weight to drop and close either gate member, a resetting element for each bar adapted to be actuated by the train after passing the tripping element to return the operated bar and tripping element to their initial position,

and an arm on each locking lever to be engaged by the train after the train has passed the crossing to swing said lever and its associate weight connected lever to raise the lowered weight to open the closed gate, means connecting both tripping elements so that both elements will be actuated to shift both bars and disengage both dogs from the dog-engaging parts of both locking levers synchronously, and means connecting both resetting elements so that both elements will be actuated to shift both bars and tripping elements back to their initial position synchronously.

In testimony whereof I affix my signature.

ALEXANDER G. SIMKINS.
